UNITED STATES PATENT OFFICE

ALBERT E. BERDON, OF EAST ORANGE, NEW JERSEY, ASSIGNOR TO A C SPARK PLUG COMPANY, OF FLINT, MICHIGAN, A CORPORATION OF MICHIGAN

LIQUID FUEL FEEDING SYSTEM

Application filed October 6, 1927. Serial No. 224,325.

This invention relates to liquid feed and supply systems, particularly for liquid fuel, and this application is drawn to subject matter which is in part disclosed in my application, Serial Number 183,103, filed April 12, 1927, which has matured into Patent Number 1,647,768, dated November 1, 1927.

The objects of the invention primarily are to provide a reserve supply in and forming a part of the feed system, which will be accumulated and maintained automatically in the ordinary operation of the system and which can be drawn upon and utilized at any time either independently of or in conjunction with the main or normal supply; to provide such a reserve in a thoroughly practical and commercial form of apparatus; also to provide the reserve or auxiliary supply in conjunction with pump mechanism and in such a way that the reserve may be utilized to continue the feed in the event of any failure in the pumping mechanism.

Other objects and the various novel features of construction, combination and relation of parts by which all are attained will appear more fully as the specification proceeds.

In the drawings accompanying and forming part of this specification, certain practical embodiments of the invention are illustrated and it will be clear from the scope of the disclosure and the breadth of the claims that the form of the actual structure employed may vary without departure from the true spirit and scope of the invention herein covered.

Figure 1 is a vertical sectional view of a form of the apparatus in which the reserve tank mechanism is embodied in and forms part of a unit with the pump mechanism.

Figure 2 is a horizontal sectional view as on the plane of line 2-2 of Figure 1 on a somewhat larger scale.

Figure 3 is a broken, sectional and more or less diagrammatic representation of a complete liquid fuel feeding system in which the reserve tank and the pump are built as separate units.

Figure 4 is a vertical sectional view of the reserve tank unit last referred to.

Figure 5 is a detail sectional illustration of the operation thereof.

In the form of the invention first disclosed, where the reserve tank is combined as a unit with the pump, the tank is illustrated as a cylindrical vessel 5 secured to and dependent from the base 6 of the pump and this base is shown as having a pump chamber 7 formed in the top of the same and closed by a flexible diaphragm 8 which is secured in place by a top or cover 9.

The base is shown provided with a valved inlet 10 opening into the pump chamber and a valved outlet 11 discharging from the pump chamber through a pipe 12 downwardly into the reserve chamber. The diaphragm forms the pumping element and is shown as actuated by a rod 13 pivoted at 14 to a lever 15 which is pivoted at 16 on the top of the pump and is actuated by a reciprocating member 17, which latter, for instance, may be mounted on a valve rod 18 of an internal combustion engine. The valve operating lever is shown as having a head 19 entered between flanges 20 of the reciprocating member 17 so that the valve rod may turn without affecting the pump driving connections.

It will be apparent from the disclosure that as the lever 15 is oscillated, the pump diaphragm will be vibrated and liquid will be thereby alternately drawn into the pump chamber and discharged from said chamber into the reserve tank.

The reserve tank is shown as having a discharge fitting or conduit 21 in the bottom of the same but the outflow therethrough is governed by a stand-pipe 22 communicating with said conduit at 23 and rising in the tank to the level which it is desired to maintain as a reserve therein. It follows from this construction that the reserve tank must be filled with liquid up to this desired reserve level before the liquid will discharge through the stand-pipe down through the outlet. In normal operation, therefore, the reserve tank will be kept filled with a desired volume of liquid, said volume in effect being "trapped" within the tank.

To enable utilization of the trapped reserve supply, a valve is shown at 24 control-

ling escape through the discharge outlet by way of ports 25 in the lower end of a tube 26 attached to and forming an upwardly inclined extension of the outlet fitting. This 5 release valve is shown as governed by a cap 27 screwed into a neck 28 in the upper, side portion of the tank and engaging a stud 29 slidingly guided in the upper end of the valve tube and having a head 30 bearing on a valve 10 closing spring 31 which engages a head 32 on the upper end of the valve stem 33, a secondary valve opening spring 34 acting against the under side of the valve stem head 32 with a force sufficient to lift the valve 15 when the pressure of the valve closing spring 31 is sufficiently relieved by the unscrewing of the cap 27.

An abutment for the lower end of the valve opening spring 34 is shown in the shape of an 20 annular washer 35 seated against an inwardly crimped shoulder 36 formed in the valve tube 26. It will be apparent that as the cap 27 is unscrewed, the tank will be vented to atmosphere, the pressure of the stronger 25 valve closing spring 31 will be relieved and the weaker valve opening spring 34 will be thereby enabled to exert its force to open the valve 24. Therefore as valve 24 is opened, the liquid in the reserve tank will be permitted to flow out through the discharge fitting by way of ports 25. Hence the reserve 30 tank may be drained down to the level of these ports by simply unscrewing the cap 27. These ports are shown placed a sufficient distance above the bottom of the tank to trap 35 any sediment or heavier foreign matter that may enter the tank.

By completely removing cap 27, access 40 may be had to the interior of the tank, for instance, to fill the same to provide an initial reserve supply before the pump is started or for initial "priming" purposes where the tank is connected with a carburetor, or the like.

45 In addition to determining the reserve level and hence the volume of the auxiliary supply, the stand-pipe 22 also serves to establish an air cushion at 37 in the upper portion of the tank above the liquid level therein. This 50 air cushion aids in preserving the continuity of flow through the tank, in eliminating pulsating effects of the pump and in maintaining a desired even pressure on the liquid.

The pump is made self-regulating to maintain 55 a desired liquid pressure by causing the diaphragm or pumping element to automatically vary its effective pumping area in accordance with requirements. This is accomplished by providing spring plates 38, 39 at 60 opposite sides of the diaphragm, which plates are radially slotted to provide the spring fingers 40 bearing against opposite faces of the diaphragm. The tips of these spring fingers are shown as turned away from the dia- 65 phragm to leave the central portion of the dia-

phragm relatively free. The spring fingers of the top plate are shown as engaged by a pressure plate 41, which in turn is acted on by a spring 42 surrounding the pump rod and tensioned by an adjustable abutment 43. The lower spring fingers are shown as similarly engaged by a pressure plate 44 acted on by a spring 45 tensioned by an abutment washer 46 and a nut 47 screwed on the lower end of the rod. 70

The self-regulating feature described enables the pump to function continuously with a constant stroke and to deliver a varying quantity of liquid, such for instance as may be required by an internal combustion engine, it being apparent that with an increase in pressure in the pump chamber, the diaphragm will flex upwardly, raising the upper spring fingers more or less, against the tension of spring 42, and that with a reduction 80 in pressure, the diaphragm will flex the lower spring fingers downwardly against the tension of spring 45. Thus, with the stroke of the pump remaining constant, the diaphragm may automatically regulate its effective 85 area, to pump less than the normal, or in fact, no liquid at all. Thus either the outlet or the inlet may be completely closed off without injuring the pump, which continues in operation with a constant stroke, merely 90 regulating its effective area one way or the other to accommodate itself to particular conditions. 95

The diaphragm is shown as rigidly clamped at its center between discs 48, secured fast on the pump rod by a nut 49, which discs are shown as cupped to present rounded surfaces to the diaphragm and to raise them so that they will serve as abutments limiting the extreme movement of the pressure plates 41, 44, 100 105 toward the spring fingers and the diaphragm.

The mounting of the pump in the head of the reserve tank leaves the pump mechanism accessible for inspection, adjustment or repairs and the combining of the pump and tank into a single unit has many advantages, particularly in the saving of external piping between the two and in the simplifying of the mounting and connecting of the devices in operative relation to the main fuel tank, carburetor, etc. The spring tensioning nuts 43 and 47 may be adjusted for the desired output and intake pressures when the pump is first assembled, but if desired, these adjustments may be subsequently made, the nut 43 being readily accessible at all times upon simply removing the slip cover 50 and the nut 47 being reached by taking off the head of the pump. 110 115 120

For some purposes it is best to have the reserve tank a unit separate from the pump. This arrangement is illustrated in Figures 3 and 4, where the tank is indicated at 51, mounted on the back of the dash of the car and the pump at 52 driven directly from an 125 130

eccentric 53 provided on the cam shaft of the engine. The carburetor of the engine is shown at 54 connected with the outlet of the tank by tubing 55, the main supply tank being shown at 56 connected with the inlet of the pump by tubing 57 and the outlet of the pump being connected with the inlet to the tank by tubing 58.

The reserve tank 51 operates on the principle of the tank first described, to automatically trap and retain a desired quantity of liquid as a reserve supply, but in order that this reserve supply may be immediately available to the driver of the vehicle, the release valve is arranged to be actuated by a dash control. This dash control is shown as a pull link 59 pivoted to a lever arm 60 on a bell-shaped cover 61 held to an annular seat 62 by a spring 63 engaging a shoulder 64 on the valve stem 65, which latter is pivotally linked to the under side of the tilting cover at 66 and has a lost motion connection at its lower end with the release valve 67.

This lost motion connection is afforded by having the body of the valve slidingly sleeved on the lower end of the stem at 68 and by providing the stem with a head 69, having a limited free movement in a cavity 70 formed in the valve body. A spring 71 engaged between the upper end of the slideable valve and the abutment shoulder 64 operates to thrust the valve to its seat and to hold it there against vibration. When, however, the cap is tilted far enough to take up the lost motion in the connection with the valve, as indicated in Figure 5, the valve will be lifted from its seat and the contents of the reserve tank will discharge by way of this release valve.

40 In this construction, as in the preceding form, the stand-pipe 72 which rises from the outlet fitting 73 determines the reserve level and also the air cushion above the same.

A priming plug may be provided in the top 45 of the tank, as indicated at 74, and a drain plug 75 may be provided in the bottom of the tank. Also the tank may be primed in the illustration by way of the valve stem passage 76, when the cover is tilted far enough 50 to uncover this passage. Normally this passage may be closed by a valve element 77 on the upper end of the valve stem. This valve and the abutment element 64 may both be screw-threaded onto the valve stem, as indicated. A practical method of making and 55 assembling the valve and lost motion connection is to construct the head 69 as a separate part, screwed or otherwise secured on the lower end of the stem after the stem has been passed through the sleeve portion of the valve body and to then fasten the point of the valve in place in the lower end of the sleeve, substantially as illustrated.

The reserve tank in the form last described 60 may be mounted on the dash or at any other

convenient position, at a level such as to properly feed the carburetor and wholly independently of the pump, which latter may be mounted down in or on the crank case of the engine.

In this form of the invention also the first 70 operation of the pump is to fill the reserve tank from the main tank and in the subsequent operation of the pump, this reserve supply is always maintained. This reserve 75 supply, therefore, is always available, for instance, after the main supply has been exhausted, or at any time before the main supply has been used up. This reserve may be used to feed the carburetor at any time 80 if the pump should fail or if the supply should otherwise be interrupted. This reserve supply also provides a definite "head" 85 on the carburetor and a lesser body of fuel apart from the main supply which is readily available for any purpose at any time it may be required.

The valve 77 in the head of the tank is normally held to its seat by the spring 63 with sufficient force to maintain the desired 90 air cushion above the liquid in the tank. When the discharge valve is tripped as indicated in Figure 5, valve 77 will be unseated, relieving the pressure and at the same time venting the tank to atmosphere 95 so that the reserve liquid will be then freely discharged by valve 67. This latter valve is shown as having a relatively long point so as to remain in guided engagement with its valve seat, this preventing disarrangement 100 of the parts. The tilting cover 61, it will be observed, serves as a dust cap preventing access of dust and moisture to the air relief valve. The shank of the pull handle 59 may be notched or shouldered, as indicated at 105 78 to interlock with an escutcheon on the dash to temporarily hold the valve tripped so that the driver may continue to operate the car without having to hold out the handle 59.

What is claimed is:

1. In liquid feeding systems, the combination with a reserve tank and pump mechanism for transferring liquid into the reserve tank, said reserve tank having means for discharging a flow of liquid therefrom and for automatically trapping a reserve body of liquid up to a predetermined limited level therein and means for simultaneously venting said tank to atmosphere and discharging the reserve liquid below said predetermined liquid level therefrom, said means including a spring loaded discharge valve and a manually operable closure for an air vent which when operated to open the same relieves the spring pressure on said discharge valve permitting the same to open. 115

2. A liquid reserve tank having a discharge valve at the bottom of the same and an air vent in the upper portion of the same, means for trapping in the tank liquid up to 120

a predetermined level and for normally discharging from the tank excess liquid above said level and means for substantially simultaneously opening said vent and the discharge valve to freely discharge the body of
5 trapped liquid below said predetermined liquid level including an air vent valve, a spring interposed between said discharge valve and said vent valve tending to seat the former and unseat the latter, manually operable means contacting with said vent valve which when moved therefrom permits the unseating or opening of said valve by said spring, and a further spring acting upon
10 said discharge valve in opposition to said first-named spring to open said valve on relief of the greater force exerted by said first-named spring upon movement of said manually operable means and opening of
15 said vent valve.
20 In testimony whereof I affix my signature.
ALBERT E. BERDON.
